SULFONYLUREA HYPOGLYCEMIC AGENTS
 Bernard Loev, Broomall, Pa., assignor to Smith Kline & French Laboratories, Philadelphia, Pa., a corporation of Pennsylvania
 No Drawing. Filed Dec. 14, 1962, Ser. No. 244,582
 5 Claims. (Cl. 260—465)

The invention described herein is concerned with novel organic compounds as well as with the processes employed in their preparation. These compounds are represented by the structural formula:

in which Z is either nitro or cyano and R is lower alkyl, cycloalkyl, phenyl, phenyl(lower)alkyl, phenoxy(lower)alkyl, (lower)alkoxyl(lower)alkyl, 1-azacyclohexane or 1-azacycloheptane.

The above compounds are hypoglycemic agents and are accordingly employed in the treatment of diabetes and other conditions where a high blood sugar level is undesirable. Being orally active, compositions of these compounds may be administered as capsules, tablets, powders, or the like. Although the dosage must of course be tailored to the particular individual and specific condition, from about 10 mg./kg. of body weight to about 50 mg./kg. of body weight generally is a highly satisfactory range.

It will be noted that the compounds of the instant invention are p-cyanophenylethyl or p-nitrophenylethylsulfonylureas. The remainder of the molecule as represented by R is not critical and may be a relatively inert group such as alkyl (e.g., butyl), cycloalkyl (e.g., cyclopentyl), phenylalkyl (e.g., phenethyl), phenyl, alkoxyalkyl (e.g., ethoxyethyl), or the like.

The hypoglycemic activity of these compounds is of considerable surprise and totally unpredictable. It is known for example that compounds of Formula II below possess hypoglycemic activity when n is 0, Y being a variable such as hydrogen, amino, trifluoromethyl, or the like:

Two exceptions to the above are those compounds wherein Y is nitro or cyano in which case the compounds are inactive.

Furthermore an increase of n to 1 results in inactive compounds, regardless of the substituents at Y. A similar lack of activity is also noted with the next homologous series wherein n is 2. It would thus appear that for a sulfonylurea of Formula II to be an active hypoglycemic agent, n must be 0 and Y a group other than cyano or nitro. Quite to the contrary I have discovered that when Y is cyano or nitro and n is 2, the resultant compounds are extremely active hypoglycemic agents.

The process involved for the preparation of the compounds of this invention involves the treatment of either the p-nitro or p-cyanophenylethylsulfonamide with an appropriate isocyanate. The reaction is preferably executed under alkaline conditions employing an inert water miscible organic solvent, e.g., acetone. The product is readily isolated by standard techniques such as acidification, evaporation of the solvent and recrystallization.

The following examples will serve to further typify the compounds and processes of this invention but should not be construed as a limitation thereof.

2

EXAMPLE 1

1-butyl-3-[β-(p-nitrophenyl)-ethylsulfonyl]-urea

To a solution of 25 g. (0.109 mole) of β-(p-nitrophenyl)-ethylsulfonamide in 109 ml. (0.109 mole) of 1 N sodium hydroxide and 109 ml. of acetone is added dropwise, with stirring and cooling, a solution of 10.8 g. (0.109 mole) of n-butyliisocyanate in an equal volume of acetone. When addition is complete, the solution is allowed to stand at ice bath temperature for one hour and then at room temperature for two hours. The acetone is then removed at 50° C. by aspirator and the resulting aqueous solution acidified with dilute hydrochloric acid to give an oil which soon crystallizes. Recrystallization from ethyl alcohol yields the product which melts at 153–155° C.

Calc.: C—47.40; H—5.81. Found: C—47.74; H—5.80.

EXAMPLE 2

1-butyl-3-[β-(p-cyanophenyl)-ethylsulfonyl]-urea

A. *β-(p-Cyanophenyl)-sulfonamide*.—To a solution of 10.8 g. (0.0539 mole) of β-(p-aminophenyl)-ethylsulfonamide in 200 ml. of water and 22.4 ml. (0.27 mole) of concentrated hydrochloric acid is added dropwise at 0° C. a concentrated solution of 3.72 g. (0.0539 mole) of sodium nitrite in water. The resultant suspension is stirred at 0° C. for an additional 5 minutes and then added dropwise with stirring at —5 to 0° C. to a previously chilled solution of 4.83 g. (0.0539 mole) of cuprous cyanide, 10.5 g. (0.162 mole) of potassium cyanide and 27.2 g. (0.324 mole) of sodium bicarbonate in 200 ml. of water. The mixture is stirred at ice bath temperatures for an additional 1.5 hours and then filtered. The residue is dried and recrystallized from ethyl acetate and hexane to yield β-(p-cyanophenyl)-sulfonamide, M.P.=105–108° C.

B. *1-butyl-3-[β-(p-cyanophenyl)-ethylsulfonyl]-urea*.—To a solution of 2.5 g. (0.0119 mole) of β-(p-cyanophenyl) ethylsulfonamide in 11.9 ml. (0.0119 mole) of 1 N sodium hydroxide and 11.9 ml. of acetone is added dropwise with stirring and cooling, a solution of 1.18 g. (0.0119 mole) of n-butyliisocyanate in an equal volume of acetone. When addition is complete, the solution is allowed to stand at ice bath temperature for one hour and then at room temperature for two hours. The acetone is next removed by aspirator at 50° C. and the resulting aqueous solution is acidified with diluted hydrochloric acid to give a dark red oil which soon crystallizes. Recrystallization from chloroform then yields the product which demonstrates a melting point of 143–148° C. (dec.).

Calc.: C—54.35; H—6.19; N—13.58. Found: C—54.04, 54.09; H—6.68, 6.46; N—13.88.

EXAMPLE 3

The following isocyanates are substituted in equivalent amounts for butyl isocyanate in the procedure of Example 1.

60   Ethylisocyanate
 n-Propylisocyanate
 Isobutylisocyanate
 Cyclopentylisocyanate
 Phenylisocyanate

65 There are thus respectively prepared upon completion of the steps therein recited the following compounds:

1-ethyl-3-[β-(p-nitrophenyl)-ethylsulfonyl]-urea
 1-n-propyl-3-[β-(p-nitrophenyl)-ethylsulfonyl]-urea
 1-isobutyl-3-[β-(p-nitrophenyl)-ethylsulfonyl]-urea
 1-cyclopentyl-3-[β-(p-nitrophenyl)-ethylsulfonyl]-urea
 1-phenyl-3-[β-(p-nitrophenyl)-ethylsulfonyl]-urea

Similarly by employing the corresponding equivalent amounts of the above isocyanates in the procedure of Example 2, Part B, there are prepared the following compounds:

1-ethyl-3-[β -(p-cyanophenyl)-ethylsulfonyl]-urea
1-n-propyl-3-[β -(p-cyanophenyl)-ethylsulfonyl]-urea
1-isobutyl-3-[β -(p-cyanophenyl)-ethylsulfonyl]-urea
1-cyclopentyl-3-[β -(p-cyanophenyl)-ethylsulfonyl]-urea
1-phenyl-3-[β -(p-cyanophenyl)-ethylsulfonyl]-urea

5

What is claimed is:

1. A compound of the formula:

10

wherein

Z is a member selected from the group consisting of nitro and cyano, and

R is a member selected from the group consisting of (lower)alkyl, cyclo(lower)alkyl, phenyl, phenyl (lower)alkyl, phenoxy(lower)alkyl, (lower)alkoxy (lower)alkyl, 1-azacyclohexane and 1-azacycloheptane.

2. A compound of the formula:

3. A compound of the formula:

15

20

25

30

4. 1-butyl-3-[β -(p-nitrophenyl)-ethylsulfonyl]-urea.
5. 1-butyl-3-[β -(p-cyanophenyl)-ethylsulfonyl]-urea.
